US00D870652S

(12) **United States Design Patent** (10) **Patent No.:** **US D870,652 S**
(45) **Date of Patent:** **** Dec. 24, 2019**

(54) **TIRE**

- (71) Applicant: **Bridgestone Americas Tire Operations, LLC**, Nashville, TN (US)
- (72) Inventor: **Paula R. Lundgren**, Akron, OH (US)
- (73) Assignee: **Bridgestone Americas Tire Operations, LLC.**, Nashville, TN (US)
- (**) Term: **15 Years**
- (21) Appl. No.: **29/686,951**
- (22) Filed: **Apr. 9, 2019**

FIG. 1 is a side perspective view of a tire showing my new design, it being understood that the tread pattern is repeated throughout the circumference of the tire;
FIG. 2 is a front elevational view thereof; it being understood that the tread pattern is repeated throughout the circumference of the tire;
FIG. 3 is a side elevational view thereof, it being understood that the opposite side is identical; and,
FIG. 4 is an enlarged fragmentary front elevational view thereof.
In the drawings, the broken lines depict environmental subject matter only and form no part of the claimed design.

1 Claim, 4 Drawing Sheets
